UNITED STATES PATENT OFFICE.

GEORGE F. PARKER, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR AN ARTICLE OF MANUFACTURE.

54,331.

Specification for Design.

Patented Dec. 23, 1919.

Application filed July 23, 1919. Serial No. 312,844. Term of patent 7 years.

To all whom it may concern:

Be it known that I, GEORGE F. PARKER, a citizen of the United States, residing at Newburyport, in the county of Essex and State of Massachusetts, have invented a new, original, and ornamental Design for an Article of Manufacture, of which the following is a specification, reference being had to the accompanying drawing, forming a part thereof.

In the accompanying drawing there is shown a representation of a circular plate, embodying the new design.

The design comprises an embellished article of manufacture and, as shown, is embodied in a plate, although the same may also be embodied in various other similar articles of hollow-ware.

It will be understood that the shape, or configuration, of the article of hollow-ware in which the design is shown as embodied, is not novel.

What is claimed, is:—

The ornamental design for an article of manufacture, as shown and described.

GEORGE F. PARKER.
